SEWING MACHINE

Filed Nov. 1, 1949

FIG. 2 INVENTOR.
KARL SCHEIWILLER
BY *Leon M. Straus*

UNITED STATES PATENT OFFICE

160,811

SEWING MACHINE

Karl Scheiwiller, Rosenberg, St. Gallen, Switzerland, assignor to Brutsch & Co., St. Gallen, Switzerland

Application November 1, 1949, Serial No. 5,824
In Switzerland July 15, 1949

Term of patent 14 years

(Cl. D70—2)

To all whom it may concern:

Be it known that I, Karl Scheiwiller, a citizen of the Swiss Confederation, and residing at Rosenberg, St. Gallen, Switzerland, have invented a new, original, and ornamental Design for a Sewing Machine, of which the following is a specification, reference being made to the accompanying drawing, forming part thereof.

Fig. 1 is a perspective view of the sewing machine, showing my new design and seen from one end of the machine and showing one side thereof;

Fig. 2 is a perspective view of the sewing machine of Fig. 1 as seen from the other end thereof and showing the other side of the machine.

I claim:

The ornamental design for a sewing machine, substantially as shown.

KARL SCHEIWILLER.
